ROTARY PUMP

Eugene Mayus, Chicago, Ill., and Walter George See, Crown Point, Ind.; said Mayus assignor to Submerged Combustion Company of America, Inc., Hammond, Ind., a corporation of Indiana

Application August 19, 1949, Serial No. 111,252

8 Claims. (Cl. 103—117)

1

This invention relates to a rotary pump and more particularly to a self-priming rotary pump having a plurality of pumping units within one housing.

An object of the present invention is to provide a rotary pump capable of handling large quantities of fluids in an exceptionally efficient manner.

Another object is to provide a rotary pump which will be self-priming and positive acting.

A further object is to provide a rotary pump which will be substantially resistant to the corrosive action of fluids and slurries.

Still another object is to provide a rotary pump employing a novel flexible impeller vane construction and a curved cam for flexing the vanes within the pump casing.

A still further object is to provide a novel rotary pump construction in which a pumping action is effected in a plurality of places within a single pump housing.

According to the invention a rotary pump having a novel impeller action and a plurality of pumping actions within one housing is provided whereby an exceptionally efficient conveyance of a fluid is effected. Flexible corrosive resistant impeller blades are flexed by passing them over arcuate cam surfaces within the pump casing. Each cam surface is reversely curved inwardly intermediate of and spaced from an outlet and its succeeding inlet so as to squeeze the flexible vanes successively toward the central axis of the pump. A resultant suction is produced at the inlet openings and a pressure is produced at the discharge or outlet openings thereby setting up a pumping action.

The objects, advantages and features of the invention will be more clearly understood by referring to the accompanying detailed description and drawings in which:

Figure 1 is an axial cross sectional view of the assembled pump;

Figure 2 is a top view of the complete pump assembly showing the drive pulley and support bearing in plan and the pump in section along the lines 2—2 of Figure 1;

Figure 3 is an enlarged partial section of the impeller and cam of Figure 1;

Figure 4 is an enlarged sectional view of the pump housing illustrating the grid construction at the inlets and outlets;

Figure 5 is a side plan view of the pump showing the manifold flanges;

Figure 6 is a top plan view of the pump housing and the manifold assembly;

2

Figure 7 is an end view of the pump housing of Figure 6;

Figure 8 is a side view of the pump assembly represented in Figures 6 and 7;

Figure 9 is a perspective of the upper portion of the manifold assembly of Figures 6, 7 and 8; and

Figure 10 is a perspective of the lower portion of the manifold assembly.

Referring to the drawings in greater detail, the pump housing 1 in Figures 1 and 2 consists of an outer casing 2 and a flange 3 to which an end plate 19 is attached. Integrally cast into the outer casing 2 are two inlet or suction openings 4 and 5, and two outlet or discharge openings 6 and 7. These openings connect the interior of the pump with the corresponding cast suction manifolds 8 and 9 and the discharge manifold 10 and 11. The manifolds are connected to supply and discharge lines (not shown) leading to and from the pump. The pump housing is supported on the base 12 by means of the support members 13, 14 and 15.

Fitted concentrically within the pump casing 2 is the impeller 16 which is mounted upon the shaft 17 and fastened thereto by means of projections 18 on the shaft interlocking with complementary wedge shaped recesses on the impeller. The shaft 17 enters the pump casing through a suitable opening in the end plate 19 and is enclosed by a packing gland 20 held in place by the retainer ring 21. The shaft 17 is supported by the bearing assembly 22 and is suitably driven through the pulley 23 to which it is secured. It will be recognized, of course, that any other means of driving the shaft 17 may be employed, such as by direct connection with a motor. The pump casing is closed at one end by the end wearplate 19 and at the other end by the removable coverplate 24.

The impeller 16, which will be described in greater detail hereinafter, is made of a molded flexible material such as rubber or plastic, and preferably of a corrosion resistant resilient material, for example, neoprene rubber. A plurality of flexible vanes 25 are integrally attached to the body portion of the impeller, extending radially from the shaft 17. As the impeller rotates concentrically within the pump casing each of the flexible vanes is caused to flex as it passes over the raised reversely curved surfaces 26 and 27 within the casing. The volume of space between a flexed vane and the preceding vane becomes larger thereby reducing the pressure within the space or creating a suction. Con-

versely the volume of space between a flexed vane and the succeeding vane becomes smaller thereby increasing the pressure within the space. The cams 26 and 27 are so arranged within the casing that the reduced pressure area is created immediately before one of the inlet openings 4 or 5 while the increased pressure area occurs before one of the outlets 6 or 7. Hence, during operation of the pump the flexing of the vanes sucks fluid into the pump in one instance and discharges fluid from the pump in the other.

Figure 3 is a sectional view of a portion of the pump casing 2, a portion of the impeller body 16 and the shaft 17, a number of the flexible vanes 25 and the cam element 26. The flexible vane 25 is of decreasing cross section from the base where it joins the impeller body 16 toward the tip. The tip 28 of the vane 25 is, however, considerably enlarged over the shaft portion, being enlarged into a round or oval shaped knob the end of which is adapted to engage the inside of the pump casing during rotation. As the vane 25 passes over the arcuate surface 26, it is flexed to such a degree that the tip 28 substantially fills the opening between the cam surface and impeller body. Hence a more complete vacuum is produced ahead of the flexed vane and a higher pressure is created in the area immediately following the flexed vane. A recessed area 29 is provided on either side of the vane 25 where it joins the impeller body 16. By this arrangement the vane may be more easily and completely flexed with less possibility of failure at the juncture. The vane also can more easily assume the extreme position shown in Figure 3 wherein the tip 28 substantially fills the space between the cam 26 and the impeller body 16.

The arcuate element 26 is reversely curved in a special way in the preferred embodiment of the invention. With respect to the center of the rotating shaft the cam surface is curved in a concave direction at either end and is curved in a convex direction at the center. Curving the surface in this fashion aids in the gradual application of the flexing force to the vanes. The curved element 26 is adapted to be slidably inserted into the wedge-shaped recess in the casing 2 and to be held in place by the shoulders 30 and 31 (Figure 3). The curved element 26 may be readily replaced by removing the coverplate 24 (Figure 2), sliding the element 26 out of its retaining recess, and inserting a new element into the recess. The impeller 16 is similarly removable by removing coverplate 24 and sliding the impeller 16 axially on shaft 17.

In Figure 4 the grid construction in the inlet and outlet openings in the casing 2 is shown. The grid 32 corresponds to the inlet opening 4 of Figure 1, and the grid 33 to the outlet opening 7 of Figure 1. The grids are positioned in such fashion that they form a portion of the circular inner face of the pump casing 2. A plurality of diagonally positioned bars 34 serve to prevent the admission of the tip 28 of the flexible vane 25 into the inlet or outlet openings during rotation. Hence the amount of wear on the tips is substantially lessened.

In Figures 5, 6, 7 and 8 the suction and discharge manifolds of the pump are illustrated. Fluid entering the pump must pass first through the suction manifold 35 which distributes the fluid through a plurality of conduits 36 and 37 and

to the proper inlet openings in the pump casing. The conduits 36 and 37 are flanged for connection to the inlet conduits 8 and 9 which communicate with the interior of the pump. In like manner fluid being discharged from the pump enters the conduits 10 and 11 and is passed through flanged connections to the discharge conduits 38 and 39 respectively. The discharged fluid is collected from the conduits 38 and 39 in the discharge manifold 40, and is thereafter passed through the flanged opening into the discharge line of the system.

In Figures 9 and 10 the suction and discharge manifold assemblies are illustrated in perspective. The flanges 41 and 42 of Figure 9 and the flanges 43 and 44 of Figure 10 are adapted for connecting to the corresponding flanges on the pump casing. The larger flanges 45 on Figure 9 and 46 on Figure 10, are adapted for connecting to the suction and discharge lines of the fluid system.

It is contemplated that pumps made according to the present invention may have any desired number of pumping units within a single casing. For example, two units are illustrated and described herein as a preferred embodiment of the invention. But any number of units such as 3 or 6 may be used merely by making certain changes in the arrangement and number of parts. By a "unit" is meant the combination of adjacent inlet and outlet openings in a pump casing and a squeezing surface intermediate said pair of openings. It will be desirable, of course, to increase the number of vanes on the impeller as the number of units is increased. It will also be evident that a more elaborate manifold assembly will be required to accommodate more than two units.

The pump described herein may be used to convey liquids of various viscosities, gases and slurries of solids in liquids up to considerable concentrations. It may be operated over a wide range of speeds depending upon the individual situation. The pump is particularly adaptable for use as a proportioning pump when driven by a direct current electric motor, or other easily adjustable power unit with a rheostat to change the driving speed. Maintenance and cleaning of the internal parts is greatly simplified because of the ease of access to the interior through the removable coverplate.

The present pump is especially useful in handling corrosive fluids such as chemical solutions, slurries and the like. The interior of the pump has no bearings and hence there is no danger of bearing corrosion. The materials used in making the pump may be varied widely in order to accommodate any type of corrosive or non-corrosive fluid. For example, in the handling of certain especially corrosive fluids, it would be desirable to use lead, stainless steel, or monel metal for the metallic parts of the pump, and a neoprene impeller and vane assembly. If the fluid is essentially non-corrosive it may be desirable to use cast iron for the pump casing and natural rubber for the impeller assembly.

The invention is hereby claimed as follows:

1. A rotary pump comprising a casing having a plurality of inlet and outlet openings disposed therein, a shaft mounted concentric to said casing, an impeller mounted on said shaft and having a plurality of flexible vanes extending radially from said shaft, and convexly curved arcuate cam elements on the inner circumference of said casing and adapted to flex said vanes and force said

vanes inwardly toward said impeller shaft intermediate an outlet and the succeeding inlet.

2. A rotary pump comprising a casing having a plurality of inlet and outlet openings disposed therein, a shaft mounted concentric to said casing, an impeller mounted on said shaft and having a plurality of flexible vanes extended radially from said shaft, a pair of convexly curved arcuate cam elements on the inner circumference of said casing and adapted for flexing and forcing said vanes inwardly toward said impeller shaft intermediate an outlet and the succeeding inlet, and inlet and outlet manifolds connected respectively to said inlets and said outlets.

3. A rotary pump comprising a casing having a plurality of inlet and outlet openings disposed therein, a shaft mounted concentric to said casing, an impeller mounted on said shaft and having a plurality of flexible vanes extending radially from said shaft, and convexly curved arcuate cam elements, forming part of the inner circumference of said casing and adapted for flexing and forcing said vanes inwardly toward said impeller shaft intermediate an outlet and the succeeding inlet, said flexible vanes being integrally molded with the body of said impeller and having a recessed area transverse to the axis of rotation of the body at the juncture of the vane with said body.

4. A rotary pump comprising a casing having a plurality of inlet and outlet openings disposed therein, a shaft mounted concentric to said casing, an impeller mounted on said shaft and having a plurality of flexible vanes extending radially from said shaft, and a pair of convexly curved arcuate cam elements forming part of the inner circumference of said casing and adapted for flexing and forcing said vanes inwardly toward said impeller shaft intermediate an outlet and the succeeding inlet, said vanes decreasing in cross-section from the base toward the tip but increasing in cross-section at the tip to form a bead thereon.

5. A rotary pump comprising a casing having a plurality of inlet and outlet openings disposed therein, a shaft mounted concentric to said casing, an impeller mounted on said shaft and having a plurality of flexible vanes extended radially from said shaft, and convexly curved arcuate cam elements forming part of the inner circumference of said casing and adapted for flexing and forcing said vanes inwardly toward said impeller shaft intermediate an outlet and the succeeding inlet, said arcuate cam elements being slidably replaceable within said casing.

6. A rotary pump comprising a casing having a plurality of inlet and outlet openings disposed therein, a shaft mounted concentric to said casing, an impeller mounted on said shaft and having a plurality of flexible vanes extended radially from said shaft, and a plurality of arcuate cam elements, forming part of the inner circumference of said casing and adapted for flexing and forcing said vanes inwardly toward said impeller shaft intermediate an outlet and the succeeding inlet, said arcuate cam elements being

concavely curved at either end with respect to said shaft and convexly curved at the center.

7. A rotary pump comprising a casing having a plurality of inlet and outlet openings disposed therein, a shaft mounted concentric to said casing, an impeller mounted on said shaft and having a plurality of flexible vanes extended radially from said shaft, and a plurality of convexly curved arcuate cam elements forming part of the inner circumference of said casing and adapted for flexing and forcing said vanes inwardly toward said impeller shaft intermediate an outlet and the succeeding inlet, said inlet and outlet openings being covered by grids comprising a plurality of diagonally positioned bars adapted to form a portion of the circumferential inner wall of said casing.

8. A rotary concentric vane-type, self priming, positive displacement pump for handling corrosive fluids which comprises a casing made of corrosion resisting metal a plurality of openings in said casing arranged in sets consisting of an adjacent inlet and outlet opening, a plurality of replaceable convexly curved arcuate cam elements forming a portion of the inner circumferential surface of said casing, said cams being positioned intermediate two sets of openings and spaced therefrom, a pair of end plates adapted to close said casing, a shaft extending through at least one of said plates and having a corrosive resistant molded resilient impeller interlocked thereto concentric with said casing, said impeller having a plurality of flexible vanes extending radially from said shaft, said vanes being adapted to be flexed by said cam elements inwardly toward said shaft during rotation of said impeller, drive means for rotating said shaft and suction and discharge manifolds connected respectively to said inlets and outlets.

EUGENE MAYUS.
WALTER GEORGE SEE.
